MAURIENNE, FRANCE

ELECTRIC FURNACE ELECTRODE

Original application filed July 8, 1926, Serial No. 121,189, and in France November 4, 1925. Divided and
this application filed July 3, 1930. Serial No. 465,719.

My invention relates to a composite vertical electrode and a head connection therefor.

My invention is particularly suitable for electric furnace operations which may be discontinued from time to time to permit the electrodes to be changed without injury to the product that is being manufactured. It is also best suited to furnace operations which employ relatively large electrodes.

One of the objects of my invention is to build a relatively large electrode at a relatively low cost.

Another object of my invention is to simplify the electrode head connection and place it so that it will not be injured by the furnace heat.

Another object of my invention is to build an electrode which may be burned very short and thereby increase the life of the electrode.

The above and other objects of my invention will be better understood from the following description and accompanying drawings, in which:

Figs. 1 and 2 are respectively a vertical section and a top plan view of one form of my electrode, and

Figs. 3 and 4 are respectively a vertical section and a top plan view of another form of my invention.

The electrode disclosed in the drawings is a carbonaceous electrode which is made of a plurality of preformed truncated sectors *y* which are cemented together with a plastic carbonaceous material. The central portion of the electrode is filled with a filler which may be similar to the plastic material between the truncated sectors *y*. The filler carries very little current, if any, and its principal purpose is to prevent the furnace heat from escaping through the center of the electrode.

The electrode in Figs. 1 and 2 is provided with a single ring of sectors *y* and in Figs. 3 and 4 there is an inner and an outer ring

of electrode sectors. The top end of the electrode is provided with a head, or an electrode holder, which comprises a water-cooled conducting element *m* attached to each of the electrode sectors *y*. The elements *m* are preferably made of bronze and the foot *t* of each of the elements is permanently secured in a recess in the top of each of the sectors by pouring molten copper *u* into the recess around the foot *t*. Each of the conducting elements *m* is provided with one or two arms *o*, which are electromechanically connected by two plates *p* in the case of a single ring of sectors as shown in Figs. 1 and 2 or by two plates *p* and two rings *q* in the case of the double ring of sectors *y* as shown in Figs. 3 and 4. This assembly is preferably made of bronze and it is held together by bolts *s* and the ring *r* forms a suitable place to attach the electrode supporting means. In Figures 1 and 2 the conducting elements *m* are connected through a plate *x* to a source of current by flexible conductors *v*, which may be attached to each of the plates *x*. For clearness only two sets of flexible conductors *v* are shown in each of the modifications. In Figures 3 and 4 the conductors *v* are connected only to the outer ring of conducting elements *m* which elements carry most of the current, since most of the current normally flows through the outer ring of electrode sectors *y*. The inner ring of sectors carry a small portion of the current and they are electrically connected to the outer conducting elements *m* through the inner elements *m* and ring *q*.

Sufficient lateral or side play is allowed in the joints between the plates *p* and arms *o* and between the ring *q* and the arms *o* to permit the electrode to expand radially upon putting the furnace into operation, and at the same time the retaining bolts *s* are screwed down sufficiently tight to maintain the proper electrical contact between the head elements.

The electrode head is cooled by a cooling fluid which circulates through the hollow conducting elements *m*. The circulating fluid is supplied to and conducted away from the passages in the conducting elements *m* by the pipes *n* which are provided with supply and outlet connections.

While I have shown two of the preferred forms of my invention, I do not wish to be limited specifically to the details shown herein as changes in these details may be made without departing from the scope of my invention as defined in the appended claims.

This application is a division of my co-pending application Serial No. 121,189 filed

July 8, 1926.

I claim:

1. An electrode comprising a plurality of parallel, longitudinal sections; a conductor attached to the top end face of each section; a radial arm on each of said conductors; a central plate above and below said arms; means for clamping said arms between said plates; and a central supporting ring fixed to said plates.

2. A composite electrode comprising a plurality of preformed, parallel, truncated sectors arranged to form a circular cross-sectional outline; a cementitious material interposed between said sectors; a core of filling material surrounded by said sectors; an electrical conductor attached to the top of each sector; a central electrode support attached to each of said conductors.

3. A composite electrode comprising a plurality of parallel, truncated sectors forming a plurality of concentric rings of electrode material; a conductor attached to each of said sectors; a radial arm on each of said sectors; a pair of annular clamping rings connecting the arms of one ring of conductors to the arms of the adjacent rings of conductors; a pair of central clamping plates clamped to the inwardly projecting arms of the inner ring of conductors; and a supporting ring fixed to said central clamping ring.

4. A composite electrode comprising a plurality of parallel preformed carbonaceous truncated sectors compactly arranged to form a circular cross-sectional outline; and a carbonaceous cementitious material interposed between said sectors.

5. A composite electrode comprising a plurality of preformed, parallel, truncated sectors arranged to form a circular cross-sectional outline; a cementitious material interposed between said sectors; and a core of filling material surrounded by said sectors.

6. A composite electrode comprising a plurality of preformed, parallel, truncated, carbonaceous sectors arranged to form a circular cross-sectional outline; a carbonaceous cementitious material interposed between said sectors; and a central core of carbona-

ceous cementitious material surrounded by said sectors.

7. A composite electrode comprising a plurality of parallel preformed carbonaceous truncated sectors arranged to form a circular cross-sectional outline; a carbonaceous cementitious material interposed between said sectors and also encasing said electrode; and a core of filling material surrounded by said sectors.

In testimony whereof, I affix my signature.

PAUL LOUIS JOSEPH MIGUET.
